TABLE RACK

Ronald J. Olson, Pelican Rapids, Minn.

Application December 2, 1949, Serial No. 6,379

Term of patent 3½ years

(Cl. D44—10)

To all whom it may concern:

Be it known that I, Ronald J. Olson, a citizen of the United States, residing at Pelican Rapids, Minnesota, have invented a new, original and ornamental Design for Table Rack, of which the following is a specification, reference being had to the accompanying drawing, forming a part thereof.

Figure 1 is a perspective view of a table rack, showing my new design;

Figure 2 is a top plan view; and

Figure 3 is a front elevational view of the same.

I claim:

The ornamental design for a table rack, as shown.

RONALD J. OLSON.
